CLAIM

The ornamental design for a compact disc storage case, as shown and described.

DESCRIPTION

FIG. 1 is a perspective view of a compact disc storage case showing our new design;

FIG. 2 is a side elevational view, the opposite side being a mirror image thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a rear elevational view of a second embodiment, with the front, sides, top and bottom views being identical to the first embodiment.
